UNITED STATES PATENT OFFICE.

CLARENCE J. HARTER, OF HARTFORD, CONNECTICUT, ASSIGNOR OF ONE-HALF TO
WILLIAM WEBB, OF BRIDGEPORT, CONNECTICUT.

RANGE-FINDING ARRANGEMENT.

1,242,686.

Specification of Letters Patent.

Patented Oct. 9, 1917.

Application filed February 10, 1916. Serial No. 77,420.

To all whom it may concern:

Be it known that I, CLARENCE J. HARTER, a citizen of the United States of America, and a resident of Hartford, county of Hartford, State of Connecticut, have invented 5 certain new and useful Improvements in Range-Finding Arrangements, of which the following is a description.

This invention relates to range finding 10 arrangements for ordnance of all types and sizes.

More specifically, the invention is directed to the arrangement for finding the range for ordnance of large and small caliber, including 15 rifles, whereby greater accuracy and precision of hitting the object aimed at and rapidity in locating the range is attained.

A particularly useful form of my invention comprises a front sight preferably of 20 closed perimeter such as a circular sight, which is fixed in position near the front of the rifle or other ordnance and a rear sight, also preferably closed in perimeter but of 25 variable extent of opening and positioned adjacent the barrel of the rifle or adjacent the rear end of the larger ordnance. A simple 30 form of such peep sight of variable extent of opening is composed of two conjugate sight plates having co-adjacent V openings but oppositely juxtaposed to form a unitary peep opening whereby upon adjustment of a suitable adjusting element said plates may at will approach or recede from each other to thereby respectively decrease 35 or increase the extent of opening of the variable sight.

A principle of my impr. ^{reg.} range finder involves the determination of the elevation of the rifle or other ordnance, *i. e.*, the distance 40 of the object of known vertical height by means of the front sight and the rear variable opening sight, said two sights being displaced from each other at a known distance, under the condition of the operator 45 adjusting the perimeter of the variable sight to visually circumscribe the image of the object aimed at, and mechanism coacting with the adjusting element of the variable opening sight to effect the proper elevation 50 of the rifle or other ordnance. In such determination, the velocity of the bullet at a definite stage is predetermined and the visual angles of an object of known dimension

at different definite distances from the observer are also predetermined.

Applying an embodiment of the invention on a rifle to a concrete illustration, we shall assume the object aimed at to be a person, *i. e.*, an object of predetermined average height, and that the bullet of the cartridge emerges from the end of the barrel at a predetermined velocity; these factors are taken into account in constructing the setting portion, usually a cam, of the mechanism. The operator or observer then 60 adjusts the variable opening sight to circumscribe the upper and lower perimeter of said variable sight as accurately as possible tangentially about the upper and lower edges of the visual image of the object. In 65 general, upon making such adjustment, increasing the extent of opening of the variable sight lowers the elevation of the rifle and decreasing the extent of opening raises the elevation of the rifle, thereby respectively 70 determining the trajectory traversed by the bullet from the end of the barrel to the center of object aimed at. To attain the desired object of the invention by use of a cam, such cam is constructed by taking 75 the above stated known quantities in account and arranging suitable coöperating means such as rollers adapted to engage said cam and controlling the position of the respective rear sight plates to another and 80 with respect to the center line of the bore of the rifle, so that upon the operator visually 85 alining the center of the rear variable opening sight, the center of the front sight and the center of the object aimed at in the same line, the center line of the barrel will be properly positioned with respect to the trajectory.

Similarly, for use on heavy ordnance, the observer visually circumscribes as accurately 90 as possible, the adjustable plates of the variable opening rear sight by means of an elevating hand wheel, or similar approved elevation determining device, thereby controlling the vertical position of the center of 95 said variable opening with respect to the center line of the bore of the ordnance by means of a similar cam constructed to effect the proper elevation for an object of known vertical height, the visual angle of said object at a known distance from the observer,

the known distance of the front sight from the rear sight, the predetermined velocity of the projectile, and other known data as will be understood by those skilled in the art.

Such relatively movable sight plates may be adjusted with respect to one another and with respect to the center line of the bore of the ordnance by combination with the cam and by means of a setting device for controlling the relation of the effective portion of the cam surface or surfaces in accordance with the vertical height of the object aimed at. For use with variable targets, the cam surface is set for the target of definite dimension preferably by means of a setting device having an indicator showing the respective dimensions of the range of variable targets, or a second or other cam surfaces may be employed in conjunction with or substitution for one another. Such indicating variable target is of use when the object aimed at is a person kneeling or lying prostrate on the ground, etc.; or for use in aiming at an object of unknown character but apparently having the same height as a fence or other object of known height.

The present invention is well adapted to modern rifles by suitably constructing the variable opening sight and its co-operating mechanism onto the sight leaf of the rear sight, and the form of my invention described hereinafter more particularly is a form which is well adapted to be employed in connection with the sight of the present United States standard Springfield rifle (model 1903).

It is desirable to provide my range finding arrangement with a sighting tube having a sighting opening closely adjacent to the eye of the marksman and to arrange such sighting tube relatively to the front and rear sights to attain alinement for the various adjustments of the variable rear sight and thereby decrease to a minimum the time required for alining the sight openings with the object aimed at.

It is also advantageous to employ lenses or other optically magnifying arrangements to enlarge the image of the object aimed at as virtually seen in the plane of the variable sight. For this purpose, it is of advantage to employ a lens having a circle or other figure of closed perimeter placed on or within said lens to serve as the front sight opening. My invention lends itself to conjoint use with the known approved correcting arrangements for windage, and drift of bullet.

Other features and objects of my invention will be more fully understood from the following description and the accompanying drawing, in which—

Figure 1 shows diagrammatically a rifle provided with a sight arrangement embody-

ing my invention and indicates the trajectory traversed by the bullet from the muzzle of the barrel of the rifle to the center of the object aimed at;

Fig. 2 is a simplified side elevational view of a rifle provided with a form of my invention comprising a front sight formed of a lens and a sighting tube to facilitate proper positioning of the eye of the marksman;

Figs. 3, 4 and 5 are companion figures showing in side elevation respectively the stock, breech and front barrel portion of a United States Springfield model rifle equipped with a sight arrangement embodying my invention;

Fig. 6 is a detail end elevation of the sighting leaf shown in Fig. 3;

Figs. 7 and 8 are companion figures showing in side elevation respectively the breech and front barrel portion of the arrangement shown in Figs. 4 and 5, but in depressed position, with certain portions removed;

Figs. 9 and 10 are companion figures showing in top plan view respectively the breech and front barrel portion of the parts shown in Figs. 4 and 5;

Fig. 11 is a rear end elevation of the breech of the aforesaid rifle and the variable sight plates, adjusting nut and regulating cam of the variable opening rear sight;

Fig. 12 is a rear end view, on a greatly enlarged scale, of the principal elements of the variable opening rear sight;

Fig. 13 is a section on the irregular line 13—13 of Fig. 12 as viewed in the direction of the indicating arrows;

Fig. 14 is a section on the line 14—14 of Fig. 12 as viewed in the direction of the indicating arrows;

Fig. 15 is the section on the line 15—15 of Fig. 12 as viewed in the direction of the indicating arrows;

Fig. 16 is the sectional view on the section line 16—16 of Fig. 12 as viewed in the direction of the indicating arrows;

Fig. 17 is the sectional view on the line 17—17 of Fig. 12, as viewed in the direction of the indicating arrows;

Fig. 18 is a detail front end elevation of the barrel and front sight;

Fig. 19 is a detail side elevation of a modified form of sighting tube and carriage therefor;

Fig. 20 is a detail front elevation of the variable opening rear sight; and

Figs. 21 and 22 are respectively rear end and side elevations of a form of my invention as applied to heavy ordnance.

Referring to Fig. 1, the front sight 1 positioned adjacent the front end of the barrel 2, of rifle 3, is indicated as an approved front sight of circular opening. The rear sight 4 comprises the upper plate 5, and lower plate 6, having conjugate openings to

provide for the sight opening 7 of variable extent, said sight plates 5 and 6 being adjustable by the knurled nut 8 to regulate the degree of opening and the position of the center of the opening 7 vertically relative to the center line 9 of the barrel 2 of the rifle. Accordingly, when the eye of the marksman is positioned at 10, and observes the object 11 of known height through the center of rear sight 7 and front sight 1, along the line 12, the center line 9 of the bore of the barrel 2 of the rifle will be properly elevated by the marksman to determine the path of the trajectory 13 traversed by the bullet discharged at a known velocity and passing through the vertical center of the object 11 aimed at. The upper visual line 14 passes from the eye of the marksman positioned at 10 tangentially with respect to the extreme uppermost point of the perimeter of the sight opening 7 through the extreme uppermost point 15 of the object 11; similarly, the visual sight line 16 passes from the eye of the marksman positioned at 10 through the extreme lowermost point of the perimeter of sight opening 7 and through the extreme lowermost point 17 of the object aimed at. Thus having the height of the object, the velocity of the bullet, the distance of the front sight from the rear sights and the distance of the eye from each said sight as known quantities, the unknown quantity, to wit, the distance of the object aimed at from the marksman, *i. e.*, the trajectory of the bullet, will be determined by proper coördination of the mechanism of the variable opening rear sight determining the vertical distance of the center of the variable sight from the center line 9 of the bore of the rifle, and thereby determining the proper elevation of the rifle. As explained generally above, and as more fully set forth hereinafter, such elevation of the rifle may be controlled by means of a properly calculated cam surface or surfaces determining the position of the center of the rear opening above the center line of the barrel.

It will be noted that the present invention when used with absolute precision affords a range finder designed to penetrate the center of the object aimed at. By means of the notches forming the conjugate peep opening of variable extent, and upon the marksman accurately circumscribing the visual image of the object aimed at both vertically and horizontally tangentially within the perimeter of the variable opening, the range will be ascertained both for the vertical center as well as the horizontal center of the object aimed at. Accordingly errors in accuracy in sighting will be reduced and thereby secure greater precision in sighting and improved convenience in sighting the object aimed at. Referring to Fig. 2, the rifle 20 is indi-

cated with the front sight 21 having an objective double convex lens 22, preferably provided with a circular black line of the proper diameter of approved construction, the leaf 23 carrying the plates 24, 25, determining the variable rear sight opening and adjusted by the nut 26, and the sighting tube 27 having the sighting opening 28, preferably of rubber or other similar resilient material to minimize the rebound of the rifle against the face of the marksman. Said sighting tube 27 preferably having the clearing lens 29 acting in conjunction with the front sight lens 22 in telescope relation to magnify the visual image of the object aimed at in the plane of the variable sight. Such sighting tube 27 is shown supported by the carriage formed by the arm 30, fixedly carried by the lever 31 fulcrumed at 32 to the leaf 25, and having its front end pivotally mounted at the point 33 approximately in the plane of the front sight 21. By such arrangement, for all adjustments of the variable sight, the sighting tube 27 will at all times be in alinement with the center of the variable rear sight opening in leaf 25, and the center of the front sight opening 22. Such sighting tube arrangement aids the marksman in locating the front and rear sights in relation to the object aimed at, and also provides simple mounting means for telescopic or similar optically magnifying means whenever desired.

Referring now more particularly to Figs. 3, 4, 5 and 6, the stock 40 of the rifle is shown provided with the plate 41 having the sighting slot 42, said plate being pivoted by means of the stud 43 within the recess 44 on the top of the stock 40, said plate being resiliently held in vertical position by means of the plate spring 45, adapted to engage the squared end 46 of plate 41. The spring 45 serves also to hold the sighting plate 41 in position within the recess 44, when folded down out of use. The sighting slot 42 may be elongated as indicated by Fig. 6. Such sighting plate 41 is employed to aid the marksman in ascertaining the vertical plane passing through the centers of the front and rear sights, and to locate the proper position of the eye for accurate sighting.

Referring to Fig. 4, the sighting tube 47 is shown as an alternative to the sighting plate 41 of Fig. 3. Said sighting tube 47 is provided with the sighting end piece 48 of rubber or other resilient material, and is carried by the bracket 49, depending in fixed relation to the balancing lever 50 pivoted at 51 onto the plate 52, slidably mounted on the sight plate 53. Said lever 50, as shown in Fig. 4, continues longitudinally of the barrel 55 of the rifle and may be bent downwardly to be brought at the side of the bar-

rel 56, to be out of the way. The front end 56 is pivoted onto the casing 57 of the front sight 58, shown as a bead having a circular opening (see also Fig. 10).

5 The specific pivotal means 51 is indicated as formed of the pin 51 having the milled head 60, said pin 51 projecting through the slot 61 in the lever 50 and tapped within the recess 62 in the slidable plate 52 (see also Fig. 11). Such arrangement affords convenience in allowing the sight leaf 53 carrying the variable opening to be folded down onto the top of the breech 64 of the rifle, as indicated in Fig. 7, during which movement the pin 51 moves along the slot 61, and the sight leaf may be locked in its folded position by tightening the head 60 against the face of lever 50. Said lever 50, as shown in Fig. 4, continues longitudinally 15 of the barrel 55 of the rifle and may be bent forwardly to be brought at the side of the barrel 55, to be out of the way. The front end 56 is pivoted onto the casing 57 of the front sight 58, shown as a bead having a circular opening (see also Fig. 10.)

The specific pivotal means 51 is indicated as formed of the pin 51 having the milled head 60, said pin 51 projecting through the slot 61 in the lever 50 and tapped within the recess 62 in the slidable plate 52 (see also Figs. 11 and 15). Such arrangement affords convenience in allowing the sight leaf 53 carrying the variable opening to be folded down onto the top of the breech 64 of the rifle, as indicated in Fig. 7, during which movement the pivot pin 51 rides along the slot 61 and the folding leaf 53 may be clamped in folded position by turning the head 60. The sighting tube 47 is advantageously carried as to permit the same to be removed from connection with the lever 50, whereupon the sighting tube 47 may be placed in the pocket of the marksman or other place for safe keeping. To this end 40 the arm 49 is held onto the rear end of lever 50 (see Figs. 9 and 4) by means of the oppositely disposed curved fingers 65 to prevent vertical displacement and similar but somewhat larger fingers 66 to prevent lateral displacement, said fingers 65, 66 being formed as projections of the plates 67, and locked by the spring 68 carrying the tapered pin 69 adapted to be seated within the opening 70 in lever 50. By springing the free end of 45 spring 68, the pin 69 will be cleared of the opening 70 and allow the plate 67, and therewith the sighting tube 47, to be slipped off of the free end of lever 50. Then, upon depressing the sight leaf 53, the balancing lever 50 will be depressed at its free or rear end, as indicated in Figs. 7 and 8.

It will be noted that the sighting tube is preferably carried by the bracket 49 through the intermediation of the hinge 71 (see Fig. 9), the hinged plates 72 and 73 being nor-

mally held in face to face contact by the retractile spring 74. Such arrangement enables the sighting tube to be swung laterally to permit the breech to be opened, as when loading the rifle.

The various parts of the variable opening sight are shown more particularly in Figs. 4 and 11 to 17 inclusive. The enlarged rear elevation shown in Fig. 12 represents the leaf 53 of the ordinary peep sight employed 75 as a general support for the variable sight mechanism carried by the slidable plate 52.

In this embodiment the milled finger nut 80 is the manual means for adjusting the extent of opening of the variable sight, and is 80 shown fixed to stud 81 journaled in an opening in plate 59 which is fixed to plate 53, and fixed to spur gear 82, driving the train of three gears 83, 84 and 85, said gear 85 being fixed to stud 86, fixed to actuating gear 87 85 meshing with the rack 88 fixed to the slid- able plate 52.

The variable opening sight is at 90 (see Figs. 11 and 12) and is formed by two co-adjacent V slots, one designated 91 at the 90 upper extremity of lower plate 92 and the other designated 93 at the lower extremity of upper plate 94. Said lower plate 92 is provided with the stud 95 which is received within the fork 96 of the bell crank 97 ful- 95 crumed at 98 and carrying the roller 99 adapted to be brought into engagement with the cam surface 100 set by means more fully described hereinafter.

Similarly the upper slot plate 94 carries 100 the stud 101 received within the fork 102 of bell crank 103 fulcrumed at 104, and carrying the roller 105 arranged in axial alinement with said roller 99 and adapted to be brought into engagement with said cam sur- 105 face 100. The V slots 91, 93 and rollers 99, 105 are shown in horizontal relation in Fig. 16. As also shown in Fig. 16, said cam 100 is formed of two outer stop surfaces 106, 107, and two inner cam surfaces 108, 108, in- 110 integral with cam arm 109, said cam arm 109 being pivotally mounted on stud 110 within the frame 111 of U-shaped cross section.

For the purpose of illustrating a method of determining the construction of the effective surface of the cam 100, we will assume that the distance between the eye and the center of the variable opening to be twelve inches, which may be chosen for the type of Springfield rifle indicated in Figs. 3 to 11 115 inclusive. Applying this data to the dia- grammatic illustration in Fig. 1, the distance from the point 10 of the location of the eye to the center of the vertical opening 7 will be twelve inches. We will assume 125 that the distance of the object 11 from the observer i. e. from the point 10 to be 100 yards and that the object 11 is a man, i. e., a target of average height, five feet, nine inches. Under these conditions, to which is 130

added the data of the velocity of the bullet, the cam 100 must be of such construction that upon accurately setting the uppermost and lowermost edges of the opening 7 respectively about the uppermost and lowermost outlines of the visual image of the object 11, *i. e.*, tangent to the respective lines 14, 16, the vertical distance of the center of the opening 7 above the center line 9 of the barrel 2 of the rifle 3 will determine the proper trajectory 13 for the above named particular circumstances. Now assume the target to be changed, but the distance of the target from the observer to remain the same as above. By similar computation, the similar sight lines 14, 16, will be ascertained and the center of the variable opening 7 determined with respect to the center line 9, and accordingly the effective portion of the cam 100 under the above named conditions will be readily computed. Similar determinations will be made for targets of other desired heights.

In like manner, the distance of the targets of desired variable heights from the observer is varied and the corresponding visual lines 14, 16, likewise derived and the vertical relation of the center of the opening 7 with respect to the center line 9 ascertained and thereby determine the respective effective surfaces of the cam 100.

It will be noted that the point 10 of location of the eye, indicated in Fig. 1, is determined by the position of the sighting plate 41 in the embodiment shown in Fig. 3, and similarly determined by the position of the sighting opening 28 in the embodiment illustrated in Figs. 2 and 4.

Referring to Figs. 12 and 13 it will be seen that said cam lever 109 extends upwardly within a suitable clearance slot in the elongated frame 111, until it is bent at 112 having the abutment 113 adapted to be engaged by the spirally shaped cam 114 controlled by the milled head 115. The indicator 116 is provided for the head 115 with indications "Man," "4 ft.," "2 ft.," etc., marked on the adjacent face of casing 111 to indicate the particular vertical height of the object aimed at. The stud 118, extending axially from and fixed to said cam 114 may be provided with notches 119 adapted to receive the chisel point of the spring pressed stop 120 to insure absolute setting of the cam lever 109 upon approximate manual movement of the setting head 115 toward the desired particular indication. The spring pressed plunger 121 (Fig. 12) serves to maintain the abutment 113 in contact with the setting cam 114. Of course, other indications of predetermined dimensions of targets in addition to or in substitution of the aforesaid indications may be employed.

Referring now to Figs. 12, 14 and 16, it will be noted that the upper plate 94 is for

constructional reasons seated in a depression within the upper body plate 122, which is in fixed relation to upper plate 94 by means of the stud 101 and by engagement of the outer edges of plate 94 against the walls of the said depression in body plate 122.

The V slotted plates are preferably arranged to be normally moved toward one another and thereby normally tend to force the respective roller 99, 105 toward the cam surface 108, to insure control of the extent of the variable opening 90 by means of the cam. Such arrangement is afforded by the duplicate retractile springs 123, extending from the pins 124, fixed to upper body plate 122 and upper plate 94, to the pins 125, fixed to the lower plate 92. As represented in Fig. 16, the lower plate 92 at its lower and broader portion is guided in the V shaped ways 126 formed in said slidable plate 52, and as indicated in Fig. 12, the upper portion of lower plate 92 embodying its V slot is narrower than its lower portion. Referring to Fig. 16 (see also Fig. 12) each pin 124, and similarly each pin 125, projects through a slot 126 in plate 52, to allow springs 123 to be positioned beyond plate 52. Also said lower plate 92 is thinner at its upper portion than at its lower, whereby the thin upper plate 94 is brought into immediate face to face engagement at their co-adjacent V slots to yield clear sighting through the variable peep opening 90.

The above described relations between the several parts of my invention effect speedy and accurate sighting. To illustrate the operation of the specific embodiment described, we will assume that the object aimed at is a man standing upright, in which case the indicator 115 is moved so that its pointer 116 indicates "Man."

Then the rifle is raised by the marksman to proper position, and the actual object sighted through the rear peep sight 90 and the front sight, with or without the auxiliary sighting tube or other aiding appliances.

Upon turning the finger wheel 80, the plate 52 will be accordingly slid relative to its supporting leaf 53, and the V notch plates 92, 94 will be controlled by the cam 100 to cause the center of the peep opening 90 to be raised or lowered relatively to the center line of the barrel so that when the marksman has accurately "sighted" the image of the object aimed at, *i. e.*, by circumscribing the extreme uppermost and lowermost portions tangentially at the respective extreme uppermost and lowermost edges of the peep opening 90, the rifle will have been adjusted by the marksman in vertical elevation to project the bullet at its predetermined speed and along the path of the tra-

jectory to encounter the middle of the object aimed at. The particular curvature of the cam 100 to effect the desired object is readily ascertained by mathematical calculation.

Now assuming the object aimed at to be four feet in height, the pointer 116 is now moved to the "4 ft." indication, and the cam lever 109 by action of the setting cam 114 will be oscillated to cause the effective cam surface 100 to be displaced from its previous position to a new position to effect proper positioning of the aperture plates 92, 94 corresponding to the target of four feet height. Similarly, the setting device and peep adjustment will be regulated for targets of two feet height, and for targets of other vertical dimensions for which provision may be made.

Whereas I have illustrated a unitary cam affording proper positioning of the peep opening relatively to the bore of the rifle, it will be apparent that individual cam surfaces for the respective target heights may be used, and suitable mechanism employed in co-operation with the setting device to project the corresponding particular cam surface to be engaged by the rollers of the aperture plates and thereby control the elevation of the rifle, as will be understood from the herein-above described data.

In the specific form of my invention shown by the drawings, I have particularly adapted the embodiment to the present sight of the United States Springfield (model 1903) rifle and employed the supporting leaf (designated 53) of the said sight also as the supporting leaf of my present invention. In such improvement, I have preserved the drift adjustment element 130 controlled by the "windage" screw for rectifying the position of the variable opening 90 laterally with respect to the vertical plane passing through the center line of the bore, as will be clear from Figs. 11, 12 and 17, the last named figure indicating the construction of the ways 131 in leaf 53 to effect the desired lateral adjustment.

The detail view shown in Fig. 18, a front end view, shows a desirable front pivoting means for the balancing lever 50. The detail view 19, shows a modification of the sighting tube, in that the tube 132 is short to avoid hinging as is necessary in the longer sighting tube 47 (see Figs. 4 and 20).

In ordnance of large caliber, including machine guns, and usually employing a hand or power wheel to elevate the ordnance, my invention is applicable thereto, as by gearing the mechanism controlling the plate corresponding to said plate 52, to the said elevating mechanism of the ordnance and properly computing the effective surface of the cam for the desired target heights, velocity of projectile, etc., as will be understood.

A form of my invention as applied to large ordnance is indicated in Figs. 21 and 22. The cannon 150 is shown journaled within the standards 151, 151, mounted on the base 152. The wheel 153, operated by hand or power, controls the elevation of the cannon.

At either side of either standard 151 is arranged the toothed segment 154 fixed as by set screws 155 to such standard 151, and the gear wheel 156, meshing with the teeth of segment 154, is fixed to the shaft 157 having a bearing at 158. The gear 159 fixed to shaft 157 and disposed within the rear sight 160, corresponds to the said gear 82 of the hereinabove described embodiment. Said gear 159 controls the positions of the upper and lower aperture plates of the rear sight 160 relative to one another and to the center line of the bore of the cannon, similarly as hereinabove described. The front sight 161 is shown fixed to the cannon 150 adjacent its front end.

The setting indicator 162 will be provided with indications of heights of variable targets as will be understood, and the cam 163 will be calculated from the predetermined quantities applicable under the conditions of use, *i. e.*, velocity of projectile at discharge from muzzle, the particular height 95 of object aimed at, the distance between the front and rear sights, the visual angle under condition of visually circumscribing the uppermost and lowermost edges of variable opening respectively about uppermost and 100 lowermost points of target, etc.

The slotted sighting plate 164 is provided to facilitate locating the common plane of the front and rear sights and determine the proper position of the eye of the observer.

It will be clear that the co-adjacent apertures need not be each of V-shape but that other constructions of aperture may be employed, and that the opening of variable extent may not be closed throughout its perimeter particularly at its horizontal edge portions.

Whereas I have illustrated my invention by reference to specific forms thereof, it will be understood that many changes and modifications may be made without departing from my invention.

I claim:

1. The combination with an ordnance, of a range finder comprising a sight, a peep sight disposed at a predetermined distance from said first named sight, means for varying the extent of opening of said peep sight, eye locating means disposed in a fixed plane relation to the plane of said peep sight, and means coacting with said varying means for controlling the elevation of the ordnance.

2. The combination with an ordnance, of a range finder comprising a sight disposed forwardly of the ordnance, a peep sight dis-

posed at a predetermined distance rearwardly of said first named sight, means for varying the extent of opening of said peep sight, eye locating means disposed in a fixed 5 plane relation to the plane of said peep sight, and means coacting with said varying means for controlling the elevation of the ordnance.

3. The combination with an ordnance, of 10 a range finder comprising a sight, a peep sight disposed a fixed distance from said first named sight, sighting means having an eye locating device in a fixed plane relation to the plane of said peep sight, means 15 for varying the extent of opening of said peep sight, means coacting with said varying means for controlling the elevation of the ordnance, and means supporting said sighting device to effect visual alinement 20 with said first named sight and said peep sight throughout the range of elevation of the ordnance.

4. The combination with an ordnance, of 25 a range finder, comprising a front sight, a rear peep sight, both said sights being in fixed relation to the ordnance, means for varying the extent of vertical opening of said rear sight, eye locating means in fixed vertical relation to the planes of said front 30 sight and said rear peep sight, and means coacting with said varying means for controlling the elevation of the ordnance.

5. The combination with an ordnance, of 35 a range finder, comprising a front sight, a rear peep sight, means for varying the extent of vertical opening of said rear sight, eye locating means in fixed relation to the planes of said front sight and said rear peep sight, and means coacting with said varying 40 means for controlling the elevation of the ordnance.

6. The combination with an ordnance, of 45 a range finder, comprising a front sight, a rear peep sight, means for varying the extent of vertical and horizontal opening of said rear peep sight, eye locating means disposed in a fixed vertical relation to said front sight and said rear peep sight, and means coacting with said varying means for 50 controlling the elevation of the ordnance.

7. The combination with an ordnance, of 55 a range finder, comprising a front sight, a rear peep sight, both said sights being in fixed relation to the ordnance, means for varying the extent of vertical and horizontal opening of said rear sight, and means coacting with said varying means for controlling the elevation of the ordnance.

8. The combination with an ordnance, of 60 a range finder, comprising a peep sight, means for varying the extent of opening of said peep sight and means coacting with said varying means for controlling the elevation of the ordnance.

65 9. The combination with an ordnance, of

a range finder, comprising relatively movable plates, a peep sight formed by co-adjacent notches in said relatively movable plates and means constructed in predetermined relation to the bore of the ordnance 70 for controlling the center of the sight relatively to the center line of said bore.

10. The combination with an ordnance, of 75 a range finder, comprising relatively movable plates, a peep sight formed by co-adjacent notches in said relatively movable plates and means constructed in predetermined relation to the bore of the ordnance for controlling the center of the sight relatively to the center line of said bore, said means comprising a cam.

11. The combination with an ordnance, of 80 a range finder, comprising relatively movable plates, a peep sight formed by co-adjacent notches in said relatively movable plates and means constructed in predetermined relation to the bore of the ordnance for controlling the center of the sight relatively to the center line of said bore, said means comprising a cam, and means adjusted by the 85 height of the object aimed at for setting said cam.

12. The combination with an ordnance, of 90 a range finder, comprising relatively movable plates, a peep sight formed by co-adjacent 95 openings in said relatively movable plates, a support for said plates, a cam controlling the relative positions of said plates, a manually operated setting device for said cam and manually operated means for further controlling said cam.

13. A range finder for ordnance, comprising relatively movable plates, a peep sight formed by co-adjacent openings in said relatively movable plates, a support for said 105 plates, a cam controlling the relative positions of said plates, and manually operated means for adjusting said cam for a target of predetermined dimension and manually operated means for further adjusting said 110 cam.

14. A range finder for ordnance, comprising relatively movable plates, a peep sight formed by co-adjacent openings in said relatively movable plates, a support having a 115 guide-way for guiding the vertical movement of said plates, a cam controlling the relative position of said plates and means for adjusting said cam for a target of definite dimension and manually operated 120 means for further adjusting said cam.

15. A range finder for ordnance, comprising relatively movable plates each having an opening arranged to jointly form a peep sight, a support having guide-ways for said 125 plates, a cam controlling the movement of said plates in said guide-way, means for adjusting said support vertically and means for setting said cam.

16. A range finder for ordnance, compris-

ing a leaf, means for hinging said leaf on the ordnance, a support carried by said leaf, means for adjusting the vertical position of said support on said leaf, vertically arranged 5 plates in said support having co-adjacent openings forming a unitary peep opening, bell cranks respectively connected to said plates, a roller carried respectively by said bell cranks, a cam adapted to be engaged 10 by said rollers, a setting device responsive to variable vertical height controlling said cam and resilient means normally tending to cause said plates to approach one another.

17. A range finder for ordnance comprising 15 a sight having a movable opening and an element provided with a sighting opening disposed to the rear of said sight and means for mounting said element in a plane related at a predetermined distance from 20 the plane of said sight.

18. A range finder for ordnance comprising 25 a sight having a movable opening, an element provided with a sighting opening, means for mounting said element to move in a substantially fixed plane, means for adjusting the position of the opening of said sight and means controlled by said adjusting means for maintaining the sighting opening of said element in alinement with the opening 30 of said sight.

19. A range finder for ordnance comprising 35 a sight having a fixed opening, a sight having a movable opening, means for adjusting the position of said movable opening, an element provided with a sighting opening disposed at a substantially constant distance from the plane of said movable opening sight and means for maintaining the sighting opening of said element in 40 alinement with said fixed opening and said movable opening.

20. A range finder for ordnance, comprising 45 a sight having a fixed opening, a support spaced from said fixed sight, means carried by said support provided with a variable sight opening, means for adjusting said variable sight opening, a sighting tube having eye locating means disposed a substantially constant distance from the plane 50 of said variable sight opening, and means controlled by adjusting means for maintaining said sighting tube in alinement with said variable opening and said fixed opening.

55 21. A range finder for ordnance comprising a sight having a fixed opening, a support spaced from said fixed sight, means carried by said support provided with a variable sight opening disposed at a substantially 60 constant distance from the plane of said variable sight opening, means for adjusting said variable sight opening, a sighting tube, a magnifying means in optical relation with said eye locating means and means con-

trolled by adjusting means for maintaining 65 said sighting tube in alinement with said variable opening and said fixed opening.

22. A range finder for ordnance comprising 70 a sight having a movable opening, said sight including a support, two plates in said support and having co-adjacent openings, guides for said plates, bell cranks respectively connected to said plates, a cam and means controlled by said cam for controlling said bell cranks.

75 23. A range finder for ordnance comprising a sight having a movable opening, said sight including a support, two plates in said support having co-adjacent openings, guides for said plates, bell cranks respectively connected to said plates, a cam and rollers controlled by said cam for controlling said bell cranks.

80 24. A range finder for ordnance comprising a sight having a movable opening including plates having co-adjacent openings forming the sight opening, a cam for controlling the relative positions of said plates and pivotal supporting means for said cam.

85 25. A range finder for ordnance comprising 90 a sight having a movable opening including two plates having co-adjacent openings forming said movable opening, a support for said plates, guides on said support for said plates, a cam and means controlled by said cam for controlling the relative positions of said plates.

95 26. A range finder for ordnance comprising 100 a sight having a movable opening including two plates having co-adjacent openings forming said movable opening, a support for said plates, guides on said support for said plates, a cam and means controlled by said cam for controlling the relative positions of said plates.

105 27. A range finder for ordnance comprising 110 a sight having a movable opening including two plates having co-adjacent openings forming said movable opening, a support for said plates, guides on said support for said plates, a cam, pivotal supporting means for said cam and means controlled by said cam for controlling the relative positions of said plates.

115 28. A range finder for ordnance comprising 120 a sight having a movable opening including two plates having co-adjacent openings forming said movable openings, a support for said plates, guides on said support for said plates, a cam, rollers for said cam and means controlled by said cam for controlling the relative positions of said plates.

125 29. A range finder for ordnance comprising 125 a sight having a variable opening including plates having co-adjacent openings forming said variable opening, a vertical standard, a support, means controlling the position of said support on said standard.

guides on said support for guiding said plates, and a cam controlling the position of said plates relative to said support.

30. A range finder for ordnance comprising a sight having a variable opening including plates having co-adjacent openings forming said variable opening, a vertical standard, a support, gearing connecting said support with said standard, a cam and 10 means controlled by said cam for controlling the relative position of said plates with respect to said support.

31. A range finder for ordnance comprising a sight having a variable opening including plates having co-adjacent openings forming said variable opening, a vertical standard, a support, gearing connecting said support with said standard, a cam, pivotal supporting means for said cam and means 15

controlled by said cam for controlling the 20 relative position of said plates with respect to said support.

32. The combination with an ordnance, of a front sight, a rear sight, means for mounting onto said ordnance said front sight and 25 said rear sight in substantially constant relation to one another, means for varying the extent of opening of said rear sight and means for locating the eye at a substantially constant distance from said rear sight. 30

In testimony whereof I have signed this specification in the presence of two subscribing witnesses.

CLARENCE J. HARTER.
